HAMMER MILL

Charles F. Crumb, Batavia, and Merrill W. Roscoe, Chicago, Ill., assignors to International Harvester Company, a corporation of New Jersey

Application June 25, 1934, Serial No. 732,284

10 Claims. (Cl. 146—79)

The invention relates to mills, especially of the hammer type, embodying a comminuting rotor directly driven, and auxiliary feed mechanisms driven indirectly from a clutch shaft, there being a speed responsive governor device on the main drive shaft to stop operation momentarily of the feed mechanisms when the speed of the rotor drops due to choking, and other overload conditions affecting the rotor.

10 The invention also relates to an improved feed for hammer mills whereby different kinds of material may be fed into the grinding chamber to be mixed in the grinding operation.

15 The objects of the invention are to provide an improved driving mechanism for the several feed means and controlled in operation by the speed of the grinding rotor.

Another object is to provide an improved feed for mixing several kinds of material in the grinding operation.

Other objects will be apparent to those skilled in the art as the disclosure is more fully made.

Briefly, these desirable objects are achieved in the form herein shown by providing a grinding chamber having a roughage feed opening disposed above a supplementary feed opening for corn kernels, or other grains. Feeding mechanisms are associated with the respective openings, said mechanisms being driven independently 25 of the rotor drive, so that, when clogging in the chamber occurs to choke and slow down the speed of the rotor, the said feed mechanisms may be momentarily stopped together until the clogging and choking condition has ended, whereupon the 30 feeding mechanisms automatically resume normal operation.

In the drawings:

Figure 1 is a plan view of a hammer mill embodying the improvements;

40 Figure 2 is a longitudinal cross sectional view of the mill taken along the line 2—2 of Figure 1;

Figure 3 is a transverse cross sectional view of the mill taken along the line 3—3 of Figure 1;

45 Figure 4 is a fragmentary elevational view of certain of the driving parts; and,

Figure 5 is a detail view of the drive clutch controlling the operation of the feeding mechanisms.

As shown in Figure 2, a reducing chamber 10 is formed by a pair of upright spaced walls 11, 12, joined by a circular drum portion 13 including a hinged cover portion 13a. The wall 12 carries a box 14 supporting bearings 15 for a transverse drive shaft 16 which protrudes out of the box 14 to carry drive pulleys 17. The shaft 16 carries

a centrifugal governor 18 for a purpose later to appear.

The shaft 16 projects into the chamber 10 where it carries the hub of a disk or rotor 19, said rotor carrying at spaced intervals pairs of brackets 20 supporting pins 21, each in turn carrying swinging hammers 22 that cooperate in the usual manner with a cylindrical screen 23 inside the drum 13 to reduce the material in process. Said rotor also carries a knife 24 cooperating with 10 a stationary knife or shear bar 25 fitted in a support 26 mounted adjacent a feed opening 27 formed in the wall 11, as shown. Below the knife support 26, the wall 11 is formed with a supplementary feed opening 28 for a purpose later 15 to appear.

The wall 11 carries a feed housing 29, in the lower end of which is journaled a transverse shaft 30 carrying a screw conveyer 31 adjacent the lower or supplementary feed opening 28. 20 Leading from the lower end of the feed housing 29 is a housing extension 32, as shown in Figure 1, carrying a communicating hopper 33 designed to feed corn or other grains through the opening 28 into the rotor chamber 10, for mixing such grains with the roughage material entering the chamber 25 over the knife 25.

Immediately above the feed screw 31 is an intermediate transverse shaft 34 also journaled 30 in the housing 29, said shaft carrying and operating a lower feed roller 35 having tooth conformations on its surface better to move the infed roughage to the knife 25, said tooth conformations operating through cut-away portions 36 in the support 26, thus compactly associating the lower feed roller and knife 25 to insure a better feed.

A third transverse shaft 37 is carried above the lower feed roller 35 in the depending legs of a vertically slid able yoke 38 guided in the end walls of the feed housing 29 and carrying suitable journals at its lower end for mounting the said shaft 37. This shaft 37 carries an upper feed roller 39 having suitable ribs thereon, as shown, for aggressively engaging the incoming roughage material. The upper end of the yoke, or bail, 38 carries one end of a tension spring 40, the other end of said spring being anchored at 41 to the top side of the feed housing 29, as shown in 50 Figure 2. The spring hook-up described is such that it constantly exerts a force that yieldingly, or resiliently, holds the upper roller 39 down to duty in close proximity to the lower feed roller 35. It is to be noted that these two feed rolls 35, 39 55

are positioned to move the roughage material over the knife 25 and through the upper feed opening 27 into the reducing chamber 10.

An elongated frame structure 42 including 5 trough-shaped sides 43 is mounted on a frame piece 44 secured to the feed housing 29 and additionally supported by a brace 45. The frame 44 carries a transverse shaft 46 substantially on the same level with the lower feed roller shaft 34 10 in a position forwardly thereof. This shaft 46 carries at one end a sprocket wheel 47 for applying power to the shaft. The shaft 46 also carries a pair of sprocket wheels 48 to drive the two spaced chains 49 of a suitable slatted, end- 15 less conveyer belt 50, upon which the roughage material is manually loaded to be delivered to the feed rollers.

The sloped trough side walls 43 are bent up abruptly at their inner ends to form vertical side 20 walls 51 connected to a pair of side angle iron frame pieces 52, the upper portion of each being vertically disposed and the lower portion of each curving inwardly and downwardly toward the feed rolls 35, 39. Across the top ends of the 25 pieces 52 is a crossbar 53, to which are secured the upper ends of a series of spaced flat strips 54, which follow generally the curvature of the frame pieces 52, the inner ends of these strips 54 sloping inwardly and downwardly, as 30 shown in Figure 2, and terminating at points adjacent the upper feed roll 39. The inner ends of the strips 54 are supported suitably in fixed position by braces 55 connected to the upper end of 35 the feed housing 29. Thus, the space between the inner end of the conveyer 50, the sides 51, and the strips 54 forms a feed throat into which the fluffy roughage material crowds before it is moved to the feed rollers by the feed aiding mechanism now to be described.

40 The side walls 51 carry journals 56 for rotatably mounting a transverse crank shaft 57 above the feed throat described, the shaft having three crank portions, each of which carries a journal block 58 for swinging feeder forks 59. Each fork 45 is U-shaped to present two fork legs or tines, as shown in Figure 1, each pair of tines passing through the adjacent registering pair of spaces or slots between the strips 54 in a manner readily understood. Extending upwardly from the journal box of each fork 59 is an extension 60, each extension at its free end being pivoted at 61 to a link 62. The other end of these links is pivotally connected to a cross shaft 63 carried by the cross-piece 53 in any desired manner. By this control 50 mechanism the lower ends of the fork prongs 59 are held to movement in an orbital path. As a result, each fork positively and aggressively engages the mass of fluffed up roughage material 55 in the feed throat at its upper part, the forks then compressing and forcing the material downwardly against the conveyer 50 and directly into the constricted inner portion of the feed throat in advance of the feed rollers 35, 39,—the material thus being evenly fed between the feed rollers,—which then take the material in a uniform mass and pass it over the knife 25 and into the chamber 10. When the forks have accomplished this function, they rise gracefully and recede 60 from the mass without interfering with the desired smooth flow of material. The drive for the 65 operative parts will now be described.

70 The main shaft 16 is driven by a belt around one of the pulleys 17 mentioned, causing the 75 rotor 19 and knife 24 to turn at high speed. Thus,

these rotor parts are directly driven. The shaft 16 carries a worm 64 driving a worm gear 65 keyed to a sleeve 66 carrying a clutch part 67, said sleeve being loose on a cross shaft 68.

As shown in Figure 1, the shaft 68 carries a 5 sprocket wheel 68a to drive a chain 69, which is trained around a sprocket wheel 70 on a shaft 71 to drive the same, said shaft being suitably supported in an appropriate framework 72. The chain 69 also drives a sprocket wheel 73 on the 10 shaft 30 to drive the screw conveyer 31. The shaft 71 further carries a spur gear 74 driving a pinion 75 on the shaft 34, that carries and drives the lower feed roller 35. A sprocket chain drive connection 76 from the shaft 34 to the shaft 46 15 drives the main feed conveyer 50 and its drive chains 49 through the sprockets 48. A sprocket chain connection 77 from the shaft 71 drives a flexible shaft 78 joined to the upper feed roller 20 shaft 37 to drive said roller. Finally, a sprocket 25 chain connection 79 from the shaft 71 drives the crank shaft 57, as shown, to operate the crank 30 feeder 59.

It is desirable to stop the drive for all of the 25 feeding mechanisms 50, 35, 39, 31 and 59 when the speed of the rotor 19 drops to a predetermined minimum because of choking in the grinding chamber 10, caused by overloading. Such stopping of the feed mechanisms is caused by the speed responsive governor 18 on the rotor shaft 30 35 40 45 heretofore described. Said governor moves a sliding collar 80 on the shaft 16, the collar in turn operating a pivoted arm 81 adapted to constitute an abutment or stop in the path of movement of a pivoted trip arm or intermittent clutch part 82 turnable fast with the shaft 68. Said part 82 carries a roller 83 pressed normally by a spring 84 into locking engagement with roller seats 85 formed on the inner periphery of the constantly rotating clutch part 67 already described. This type of intermittent dog clutch is the usual clutch employed in harvesters and is well understood to those skilled in the art and, therefore, need not be more fully described.

In operation, when the shaft 16 is pulley and belt driven, the rotor 19 turns at high speed, so that the hammers 22 operate effectively to grind the material fed into the drum. At the normal high speed of the shaft 16 the centrifugal governor through the collar 80 holds the stop arm 81 50 55 60 65 70 75 80 out of the path of rotation of the driven clutch part 82, the spring 84 being effective to cause the roller 83 to lock with the constantly running clutch part 67 to cause rotation of the cross shaft 68, the latter moving at a relatively slow speed because of the reduction gearing 64, 65. The shaft 68 thus drives through the several connections, the feed rollers 35, 39, the screw conveyer 31, the roughage feed conveyer 50, and the feed aiding forks 59. If the speed of the rotor goes down because of clogging, the governor 18 becomes instantly operative to slide the collar 80 to move the stop 81 into position to engage the clutch part 82, as shown in Figure 5, to stop the drive by locking the shaft 68 stationary. The governor automatically moves the stop 81 out of the clutch holding position when the clogging condition stops and the rotor regains normal speed.

70 From this description it can now be seen that an improved feed mechanism and control have been provided which achieve all of the desirable objects heretofore recited.

75 It is the intention to cover all changes and

modifications not departing from the spirit and scope of the invention which has been defined in the following claims.

What is claimed is:

5. 1. A feed mill comprising an upright drum enclosing a grinding rotor, said drum having a roughage feed opening, a shear bar carried in the opening, a knife on the rotor cooperating with the shear bar to cut roughage fed through said opening, a pair of superimposed feed rollers adjacent said roughage feed opening, means to feed roughage between said rollers, said drum having an auxiliary feed opening arranged below the roughage opening and shear bar, a hopper for directing other material to a point under the feed rollers adjacent said auxiliary opening, and a screw conveyer below the feed rollers and disposed at substantially a right angle to the aforementioned feed means for moving the said other material through the auxiliary opening into the drum to be ground and mixed with the roughage.
2. A feed mill comprising an upright drum enclosing a grinding rotor, said drum having a roughage feed opening, a shear bar carried in the opening, a knife on the rotor cooperating with the shear bar to cut roughage fed through said opening, a feeder housing adjacent the drum, a pair of superimposed feed rollers in the housing and adjacent said roughage feed opening, means to feed roughage to said housing and between said rollers, said drum having an auxiliary feed opening arranged below the roughage opening and shear bar, a hopper for directing other material into the lower end of the feeder housing below said feed rollers and adjacent said auxiliary feed opening, and a screw conveyer in the bottom of the feed housing disposed at substantially a right angle to the roughage feeder and directly below the feed rollers for moving said other material through the auxiliary feed opening into the drum to be ground and mixed with the roughage.
3. A grinding mill comprising an upright drum having a grinding rotor therein and formed on one face with a pair of vertically aligned feed openings, a feed housing adjacent said openings, three substantially vertically aligned shafts in said housing, a feed roller on each of the upper two shafts adjacent the upper feed opening, a screw conveyer on the lower shaft adjacent the lower opening, means to feed roughage to the feed rollers, and means to feed other material to the screw conveyer, said screw conveyer moving the other material through the lower feed opening into the drum.
4. A mill comprising an upright drum carrying a main horizontal drive shaft and a rotor thereon within the drum, a governor on the drive shaft, said drum provided on one face with a pair of vertically spaced feed openings, a feed housing adjacent the openings, a pair of feed rollers in the housing for delivering roughage into the drum along a line at right angles to the face of the rotor through the upper opening, a screw conveyer in the housing below the feed rollers for delivering other material into the drum through the lower opening and at substantially a right angle to the aforementioned line of feed, a feeder frame adjacent the feed housing and forming a throat portion in advance of the feed rollers, a conveyer on the frame for feeding roughage to the feed rollers, a fork feeder over the throat to move the material from the conveyer between the feed rollers, a shaft including a clutch driven from the main drive shaft, means for driving the conveyer, fork feeder, feed rollers and screw conveyer from said driven shaft.
5. A mill comprising an upright drum carrying a main horizontal drive shaft and a rotor thereon within the drum, said drum provided on one face with a pair of vertically spaced feed openings, a feed housing adjacent the openings, a pair of feed rollers in the housing for delivering roughage into the drum through the upper opening, a screw conveyer in the housing below the feed rollers for delivering other material into the drum through the lower opening, a feeder frame adjacent the feed housing and forming a throat portion in advance of the feed rollers, a conveyer on the frame for feeding roughage to the feed rollers, a fork feeder over the throat to move the material from the conveyer between the feed rollers, a shaft including a clutch driven from the main drive shaft, means for driving the conveyer, fork feeder, feed rollers and screw conveyer from said driven shaft.
6. A mill comprising an upright drum carrying a main horizontal drive shaft and a rotor thereon within the drum, a governor on the drive shaft, said drum provided on one face with a pair of vertically spaced feed openings, a feed housing adjacent the openings, a pair of feed rollers in the housing for delivering roughage into the drum through the upper opening, a screw conveyer in the housing below the feed rollers for delivering other material into the drum through the lower opening, a feeder frame adjacent the feed housing and forming a throat portion in advance of the feed rollers, a conveyer on the frame for feeding roughage to the feed rollers, a fork feeder over the throat to move the material from the conveyer between the feed rollers, a shaft including a clutch driven from the main drive shaft, means for driving the conveyer, fork feeder, feed rollers and screw conveyer from said driven shaft.
7. A mill comprising a drum carrying a main drive shaft and a rotor thereon within the drum, said drum provided on one face with a pair of spaced feed openings, a feed housing adjacent the openings, a pair of feed rollers in the housing for delivering roughage into the drum through one opening, a screw conveyer in the housing for delivering other material into the drum through the other opening, a feeder frame adjacent the feed housing and forming a throat portion adjacent the feed rollers, a conveyer on the frame for feeding roughage to the feed rollers, a fork feeder to move the material from the conveyer to the feed rollers, a shaft driven from the main drive shaft, and means for driving the conveyer, fork feeder, feed rollers and screw conveyer from said driven shaft.
8. A mill comprising an upright drum carrying a main horizontal drive shaft and a rotor thereon within the drum, a governor on the drive shaft, said drum provided on one face with a

pair of vertically spaced feed openings, a feed housing adjacent the openings, feed rollers in the housing for delivering roughage into the drum through the upper opening, a screw conveyer in the housing below the feed rollers and disposed at substantially a right angle to the axis of the rotor for delivering other material into the drum through the lower opening, a feeder frame adjacent the feed housing and forming a throat portion in advance of the feed rollers, a conveyer on the frame for feeding roughage to the feed rollers, a fork feeder over the throat to move the material from the conveyer to the feed rollers, a shaft including a clutch driven at reduced speed from the main drive shaft, means for driving the conveyer, fork feeder, feed rollers and screw conveyer from said clutch shaft, and means operated by the governor for throwing out the clutch to stop the drive to all the feeding means mentioned when the speed of the rotor shaft falls to a predetermined minimum.

9. A mill comprising an upright drum carrying a main horizontal drive shaft and a rotor thereon within the drum, a governor on the drive shaft, said drum provided on one face with a pair of vertically spaced feed openings, a feed housing adjacent the openings, a pair of feed rollers in the housing for delivering roughage into the drum along a line at right angles to the face of the rotor through the upper opening, a screw conveyer in the housing below the feed rollers for delivering other material into the drum through the lower opening and at substantially a right angle to the aforementioned line of feed, a feeder frame adjacent the feed housing and forming a throat portion in advance of the feed rollers, a conveyer on the frame for feeding roughage to the feed rollers, an overhead feeder

above the throat to cooperate with the conveyer to move the material positively between the feed rollers, a shaft including a clutch driven from the main drive shaft, means for driving the conveyer, overhead feeder, feed rollers and screw conveyer from said clutch shaft and means operable by the governor for throwing out the clutch to stop the drive to all of the feeding means when the speed of the rotor falls to a predetermined minimum.

10. A mill comprising an upright drum carrying a main horizontal drive shaft and a rotor thereon within the drum, a governor on the drive shaft, said drum provided on one face with a pair of vertically spaced feed openings, a feed housing adjacent the openings, horizontal feed rollers in the housing for delivering roughage between them into the drum through the upper opening, a conveyer in the housing below the feed rollers for delivering other material into the drum through the lower opening, a feeder frame adjacent the feed housing and providing a throat portion in advance of the feed rollers, a roughage conveyer on the frame for feeding roughage to the feed rollers, a feeder over the throat and roughage conveyer to move the material with the roughage conveyer to and between the feed rollers, a shaft including a clutch driven at reduced speed from the main drive shaft, means for driving the roughage conveyer, feeder, feed rollers and first conveyer from said clutch shaft, and means operated by the governor for throwing out the clutch to stop the drive to all the feeding means mentioned when the speed of the rotor shaft falls to a predetermined minimum.

CERTIFICATE OF CORRECTION.

Patent No. 2,059,316.

November 3, 19

CHARLES F. CRUMB, ET AL.

It is hereby certified that error appears in the above numbered patent requiring correction as follows: In the grant, lines 1 and 2, and in the heading to the printed specification, lines 3 and 4, in the residences of the patentees, for "Batavia" read Chicago and for "Chicago" read Batavia; and page 3, second column, line 62, claim 7, after "housing" insert the words disposed at substantially a right angle to the axis of the rotor; and that the said Letters Patent should be read with these corrections therein that same may conform to the record of the case in the Patent Office.

Signed and sealed this 5th day of January, A. D. 1937.

Henry Van Arsdale

(Seal)

Acting Commissioner of Patents.
